(57) **CLAIM**

The ornamental design for luggage, as shown and described.

DESCRIPTION

FIG. 1 is a top, front and right side perspective view of luggage embodying my new design shown in a closed configuration;

FIG. 2 is a top, front and right side perspective view similar to FIG. 1, illustrating extension of a handle;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top, front and right side perspective view of the luggage of FIG. 1, in a partially open configuration;

FIG. 10 is a top, front and right side perspective view of the luggage of FIGS. 1 and 9, in a fully open configuration;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof; and,

FIG. 16 is a bottom plan view thereof.
